UNITED STATES PATENT OFFICE.

FRED H. C. WOOLLEY, OF MEDFORD, ASSIGNOR TO THE UNITED SOCIETY OF CHRISTIAN ENDEAVOR, OF BOSTON, MASSACHUSETTS.

DESIGN FOR A BADGE.

SPECIFICATION forming part of Design No. 18,184, dated March 13, 1888.

Application filed February 7, 1888. Serial No. 263,319. Term of patent 14 years.

To all whom it may concern:

Be it known that I, FRED H. C. WOOLLEY, a citizen of the United States, residing at Medford, in the county of Middlesex and State of Massachusetts, have invented a new and original Design for Badges, of which the following, taken in connection with the accompanying drawings, is a specification.

Figure 1 is a plan view of my newly-designed badge. Fig. 2 is a plan view of the badge having a jewel set therein. Fig. 3 is a plan view showing the badge as a pendant, and Figs. 4 and 5 are views of the back of the badge, showing it as a pin.

My design consists of an outer narrow rim, A, in the form of the circumference of a circle, having a portion removed so as to form an opening, B, at the right, as shown, the opening being about one tenth of the entire circumference in width, and certain bars arranged within the said rim in the following manner, to wit: Opposite the opening, with its ends resting against the inside of the rim, as shown, is the bar *a*, and at each end of the bar *a*, con-

nected therewith, is a bar, *b*, as shown, at right angles to the bar *a*, extending to and touching the inside of the rim near the opening. Midway between the bars *b*, and with its general direction parallel therewith, is the bar *c*, somewhat shorter than bars *b*, curved, as shown, and extending on both sides of bar *a*. The bar *c* extends on the left of bar *a* to nearly the inside of the rim, and is cut off at an angle, as shown. At the intersection of the bars *a* and *c* a jewel, *d*, may be set, as shown in Fig. 2. 35

I claim—

The design for a badge herein shown and described, consisting of the rim A, having the opening B, and the bars *a*, *b*, *b*, and *c*, arranged within the rim, as shown and described.

In testimony whereof I have signed my name to this specification, in the presence of two subscribing witnesses, on this 4th day of February, A. D. 1888.

FRED H. C. WOOLLEY. [L. S.]
